UNITED STATES PATENT OFFICE.

ANDREW J. CHRISTY AND EDWARD O. BENNETT, OF SAN FRANCISCO, CALIFORNIA, ASSIGNORS TO SAMUEL B. PAIGE, EDWARD H. MOORE, AND CHARLES J. MOORE, ALL OF SAME PLACE.

ORE CRUSHER AND GRANULATOR.

SPECIFICATION forming part of Letters Patent No. 364,480, dated June 7, 1887.

Application filed April 17, 1886. Serial No. 199,928. (No model.)

To all whom it may concern:

Be it known that we, ANDREW J. CHRISTY and EDWARD O. BENNETT, citizens of the United States, residing at San Francisco, in the county of San Francisco and State of California, have invented certain new and useful Improvements in Ore Crushers and Granulators; and we do hereby declare the following to be a full, clear, and exact description of the invention, such as will enable others skilled in the art to which it appertains to make and use the same.

Our invention relates to crushers and granulators for ore, (or coal or rock,) and has for its object the construction of a machine for this purpose which shall be capable of reducing ores by a purely granulating process, without lamination or mashing of the particles of precious metal, so that said particles shall, when freed from the embedding quartz, possess the same shape and characteristics as when in the quartz; also, that a greater per cent. of yield and a more complete separation of the valuable matter will take place in the succeeding process of amalgamation. We accomplish these ends by the peculiar form and manner of operating the jaws. The form of the crushing-jaws is such as to give a gradually tapering or reduced space between them at the top, extending down about one-half of their height and terminating in a narrower but uniform curved space, one of the jaws being convex and the other concave for this purpose. These jaws are so operated as to cause the crushing to be done in the upper contracting space, which portions of the jaws shall have considerable movement to and from each other, while the granulation is accomplished in the lower curved space where the jaws have but slight movement to and from each other with a largely-increased curvilinear movement, which increases the rubbing and granulating effect in the lower portion of the jaws while the mashing or flattening of the valuable particles is entirely obviated.

The jaws have a single common center and receive motion from a cranked shaft in such manner as to cause their movement in the required opposite directions.

The manner in which we construct and operate our device to produce the ends above indicated will be more fully explained in the following detailed description.

The accompanying drawings illustrate what we consider the best means for carrying our invention into practice.

Figure 1 is a side elevation of our machine. Fig. 2 is a plan view of the same. Figs. 3 and 4 are respectively front and rear views of the machine. Fig. 5 is a longitudinal section on line $x x$, Fig. 2, the ends of the machine being reversed. Fig. 6 is a detail view of the cranked shaft.

Similar letters of reference indicate corresponding parts in all the figures where they occur.

A is the fixed framing of the crusher, certain parts of which will be designated by modified characters, as may be required, in giving a detailed description of our invention.

B is an eccentric shaft (the eccentrics being oppositely disposed thereon) mounted in bearings $a' a'$ on standard A' A' of frame A.

C is a fixed shaft mounted upon studs or standards A $\times$ of frame.

D and D $\times$ represent the crushing-jaws, one of which, D $\times$, is pivotally mounted on the fixed shaft C, while to the other, D, are pivotally attached the yokes E, one on each side, by means of pivots or shafts h h' , extending through said jaw, the shaft h' also extending through slots h^* in the ends of the lower limbs of said yokes. These yokes are also pivotally mounted on the fixed shaft C and serve to hold the jaw D in proper relation to the jaw D $\times$, whereby said shaft becomes the center of motion for both jaws. The slotted ends of the lower limbs of the yokes E are provided with set-screws i i , (Figs. 1 and 3,) whereby proper working distance between the jaws and compensation for their wear may be maintained.

The jaws are operated from the eccentric shaft B by means of the pitmen b and $b' b'$ attached thereto, the former being coupled to the jaw D preferably at or below the middle height thereof and the two latter to the jaw D $\times$ at its top.

The cranks or eccentrics on shaft B, as best shown in Fig. 6, are so disposed as to cause the jaws to move in opposite directions.

An analysis of the movements and operation of the parts thus far described will show that the jaws are caused to have a considerable back-and-forth movement to and from each other with but little if any rubbing or vertical movement at their upper ends, while the 10 action is reversed at their lower ends, and the rubbing or vertical movement is largely increased, while the opposing reciprocation is almost entirely absent. These effects are due to the manner of coupling and mounting the 15 jaws. The resultant function achieved by this movement is to crush and break up the quartz in the upper portion of the jaws, while the granulation is completed below without laminating or mashing the precious material, 20 the partially reduced or broken lumps and craggy particles of the quartz aiding to free the precious particles by contact with each other without bruising or mashing the valuable particles. This effect is attained, to a con- 25 siderable extent, by the manner of operating the jaws regardless of the shape thereof, and we may use the construction of parts thus far described with any form of jaw; but we employ a form of jaws which increases the utility 30 of the machine in the direction above stated to a very great degree, and we prefer this form of jaw to the ordinary form for reasons which will now appear.

To the body portions D D^x of the jaws we 35 apply the faces D' D^z, which are formed of steel or chilled iron. The faces are formed with inclined portions d' d^z, which recede from each other at the top and converge to about mid-height of the jaws. From this point 40 downward the faces of the jaws run practically parallel with each other, but are curved, as shown, one being concave, as shown at d^z, and the other convex, as shown at d'. With these forms of jaws the process of granulation with- 45 out lamination is pursued in a most complete and perfect manner. The upper contracting

or reversely-inclined portions are given a con- siderable movement to and from each other and have great crushing power, while this movement in the lower curved and parallel 50 portions is scarcely noticeable, but an inverse curvilinear or reciprocating movement is ob- tained, which tends to separate the precious particles from the inclosing quartz without laminating or mashing them.

The jaws may be smooth or corrugated.

If desired, fly-wheels may be applied to the cranked shaft to secure steady movement.

Between the yokes E and the sides of the jaws we place side plates or cheeks, G G, which 60 are made removable and can be replaced by others when worn out. These serve both to steady and sustain the jaws laterally and also to keep the material under treatment between them.

Having thus described our invention, what we claim, and desire to secure by Letters Patent, is—

1. The combination of the fixed shaft C, the jaws D D^x, the yokes E, and means, substan- 70 tially as described, for operating the jaws, the jaw D^x being pivotally mounted on the fixed shaft, and the jaw D pivotally attached to yokes E, which are also pivoted to the fixed shaft.

2. The combination, with the fixed shaft C, the jaw D^x, and the yokes E, said jaw and the yokes being pivotally mounted on said shaft, of the jaw D, pivotally secured to said yokes, whereby it is held in proper relation 80 to jaw D^x, the eccentric shaft B, pitman b, connecting said shaft with one of said jaws at its middle height, and the pitmen b' b', connecting it with the opposing jaw at its top, substan- tially as and for the purpose set forth.

In testimony whereof we affix our signatures in presence of two witnesses.

ANDREW J. CHRISTY.
EDWARD O. BENNETT.
